UNITED STATES PATENT OFFICE.

THEODORE L. VALERIUS, OF FORT ATKINSON, WISCONSIN, ASSIGNOR TO THE CREAMERY PACKAGE MANUFACTURING COMPANY, OF CHICAGO, ILLINOIS, A CORPORATION OF ILLINOIS.

BOTTLE FILLING AND CAPPING MACHINE.

1,290,424.

Specification of Letters Patent.

Patented Jan. 7, 1919.

Application filed April 16, 1915. Serial No. 21,640.

To all whom it may concern:

Be it known that I, THEODORE L. VALERIUS, a citizen of the United States, residing at Fort Atkinson, in the county of Jefferson and State of Wisconsin, have invented certain new and useful Improvements in Bottle Filling and Capping Machines, of which the following is a specification.

This invention contemplates an improved machine for acting upon bottles, and is herein shown as embodied in a combined machine adapted to fill and apply the disk caps to bottles used for milk and cream. Certain features of the invention, however, are applicable to separate bottle-filling machines or bottle-capping machines as well as to a combined machine of the character mentioned.

Milk bottles are of different sizes which vary in height and diameter according to the size, and it is one of the objects of the present invention to produce a machine which is quickly and conveniently adjustable to accommodate bottles of any size. To this end means is provided for varying the distance between the filling and capping devices, on the one hand, and the bottle - supporting means, on the other, so that the filling and capping devices will be positioned at a suitable height to operate upon the particular size of bottles being passed through the machine. Also the slide for horizontally advancing the bottles is arranged to be adjusted to different positions so as to properly center the different sizes of bottles with respect to the filling and capping devices.

The invention also refers to an improved mechanism for co-operatively elevating and advancing the bottles.

Various other objects of an ancillary nature and objects relating to details of construction will be understood from the following description.

In the accompanying drawings, Figure 1 is a side elevation of a machine embodying the features of my invention. Fig. 2 is an end elevation with a portion of the base broken away to disclose the mechanism therein contained. Fig. 3 is a sectional detail view illustrating one of the filling valves and the means for suspending it in inoperative position. Fig. 4 is a fragmental plan view on a reduced scale showing the valve

suspending means. Fig. 5 is an enlarged transverse sectional view through the lower portion of the machine taken in the plane of line 5—5 of Fig. 1. Fig. 6 is a horizontal section in the plane of line 6—6 of Fig. 2, showing the bottle-supporting and advancing means in top plan view. Fig. 7 is a horizontal section in the same plane as Fig. 6, but with the bottles and their advancing slide removed.

The preferred form of my invention is shown in the drawings and will be herein described in detail, but it should be understood that I do not thereby intend to limit the invention to the construction disclosed, the scope of the invention being pointed out in the appended claims.

The machine comprises a suitable support in the form of a hollow base 10 of rectangular or frusto-pyramidal form. A drip-pan 11 is mounted upon and closes the upper end of the base, and a bottle-supporting table 12 is mounted upon the upper ends of a plurality of studs 13 which rise from the drip-pan 11. 9 (Fig. 1) indicates a drain pipe for the drip-pan. The middle portion of the table 12 is cut out as shown in Fig. 7 to accommodate the vertical movements of the elevator, and the slide means for advancing the bottles *a* is mounted for horizontal reciprocation on the table as will be later described more in detail. The right-hand end of the machine as it appears in Fig. 1, is herein referred to as the front end, the bottles being placed on this end of the table by the attendant and being then automatically moved rearwardly step-by-step through the machine.

Two standards 14 are mounted for vertical sliding movement in bearings 15 on the drip-pan 11, and on the upper ends of these standards the milk tank 16 is supported. The tank is equipped with a suitable number of filling valves 17, which may be similar to that shown in my prior Patent No. 888,769, there being in the present instance four rows of valves, each row having four valves therein. The construction of these valves and the means for suspending one or more rows in inoperative position will be described later. On one side of the tank 16 is mounted a bracket 18 in which is supported 100 a row of bottle-capping devices 19 adapted

to be actuated by the upward movement of the bottles. A capping device of this character is disclosed in a copending application filed by Theodore L. Valerius and Olaf 5 Larsen, Serial No. 850,123, (Patent No. 1,139,931) and I have deemed it unnecessary to illustrate the details herein.

The lower ends of the standards 14 are screw-threaded and are mounted for vertical 10 movement in suitable guide bearings 20 on the outer sides of the base 10. Interiorly-threaded sleeves 21 surround the lower ends of the standards 14 and rest upon the bearings 20 to support said standards. The 15 sleeves 21 have spiral gears 22 fixed thereon and meshing with spiral gears 23 fixed on a horizontal shaft 24 which extends through the base, the latter shaft having a squared end adapted to receive a wrench or crank 20 (not shown) whereby said shaft may be rotated to cause vertical movement of the standards 14 and therefore of the tank 16. A nut 25 surrounding each standard 14 beneath the bearing 15 is arranged to lock the 25 standard against movement after it has been adjusted to position the tank at the desired height.

The bottle-elevating and advancing mechanism is driven from an electric motor 26 30 which is mounted, in the present instance, beneath the projecting rear end of the table 12. The drive-pulley 27 of this motor is connected by a belt 28 to a pulley 29 loose on a shaft 30 which is mounted in the base 35 10. The pulley 29 has clutch teeth thereon (Fig. 5) arranged to be engaged by a slideable clutch collar 31 which is splined on the shaft 30, said collar being slideable by means of a forked arm 32 which is fixed on a rock- 40 shaft 33 running from front to rear along the base and having hand-levers 34 on both ends thereof. The rock-shaft 33 is mounted in bearings 35 upon the outer ends of two transverse tie-and-brace rods 36 which extend from side to side of the base 10. In 45 both ends of the base are door openings which are closed by doors 37.

A pinion 38 is fixed on the shaft 30 and meshes with a gear 39 fixed on an intermediate shaft 40, the latter shaft having a pinion 41 thereon which meshes with a gear 42. The latter gear is bolted to the hub 43 of a rotary cam member 44 which is loosely mounted upon a transverse shaft 45 55 fixed in the base 10. The cam member is confined between collars 46 and 47 on the shaft. 48 indicates a friction device which surrounds the hub of the gear 39, said device comprising two complementary semi-cylindrical halves yieldingly pressed together and provided with an extension or arm 49 which overlies and bears against the shaft 45. This friction device is provided for the purpose of preventing overrunning 60 of the mechanism by momentum

The bottle elevator comprises a post 50 mounted for vertical sliding movement in a bearing 51 on the drip-pan 11, the lower end of said post comprising two bifurcated plates 52 which straddle the collar 46 and 70 the hub of the cam member 44, respectively, for guiding the post. A roller 53 is mounted on a pin fixed in the plates 52 and bears against the periphery of the cam member 44, whereby the rotation of the cam member will 75 operate the elevator. On the upper end of the post 50 is mounted a platform 54 having vertically disposed ribs 55 running longitudinally of the machine and each positioned beneath a longitudinal row of bottles. On the upper ends of these ribs are 80 fixed horizontal plates 56 upon which the bottles rest. Each plate 56 is long enough to support six bottles.

The bottle-supporting table 12 is provided 85 on its upper face with two ribs 57 positioned at opposite sides of the central opening 58 in the table and running lengthwise of the table. At its rear end the table is also provided with three intermediate ribs 59 running from the rear edge of the opening 58 parallel to the ribs 57 and adapted to form guide channels for the rows of bottles on the table. A bottle-advancing slide 60 comprises a transverse portion 61 at its front end 90 and a plurality of parallel bars 62 extending rearwardly therefrom and having laterally extending lugs 63 which are so located as to provide individual spaces between the bars 95 for the bottles. The lugs 63 are beveled on their leading edges so that each pair provides a crotch for centering a bottle. The bars 62 have grooves on their under sides to receive the ribs 57 and 59 on the table whereby the slide is guided for horizontal reciprocation. The bars are not connected with each other except by the transverse portion 61 on the front end of the slide so that the ribs 55 and plates 56 on the elevator may 100 pass up freely between the bars 62 to permit the bottles to be raised to a plane above the slide 60. While the bottles are held raised the slide is moved forwardly free of the bottles. The plates 56 of the elevator are suitably shaped or notched, as shown in 105 Fig. 7, so as to pass the lugs 63 on the bars 62. Said bars are provided on their front ends near the transverse portion 61 with up-standing guard flanges 64 (Figs. 1, 2 and 6) which extend between the bottles of the first 110 two rows to facilitate placing the bottles in their spaces.

The slide 60 is arranged to be reciprocated by two arms 65 (Fig. 2) located at opposite sides of the base 10 and fixed at their lower 115 ends upon a rock-shaft 66 mounted in the base, the upper ends of said arms being bifurcated to receive two pins 65^a projecting from opposite sides of the slide. The slide 120 may be readily removed from the machine 130

to facilitate cleansing by lifting it off its guide ribs 57, 59, and out of association with the actuating arms 65.

The shaft 66 (see Figs. 1 and 2) is rocked 5 by an arm 67 fixed thereon, the lower end of said arm being connected by an adjustable link 71 to the lower end of a lever 72 pivoted on a shaft 73. A roller 74 is mounted at the joint between the link 71 and lever 10 72 and is arranged to bear against the periphery of the cam member 44. The upper end of the lever 72 is attached to one end of a coiled tension spring 75, the opposite end of which spring is anchored to 15 the base 10. This spring acts to move the slide 60 in the direction opposite to that caused by the cam 44. The link 71 comprises a central rod having oppositely pitched screw threads on its ends which engage 20 in heads attached to the arm 67 and lever 72, respectively. A hand wheel 68 having notches 68^a in its periphery is fixed on the middle of this rod and a latch 69 pivoted on the arm 67 is arranged to engage 25 in the notches to lock the wheel. One or both of the ribs 57 on the table 12 are provided with gage marks 70 to indicate the correct position of the slide 60 on the table for the different sizes of bottles, the mark 30 nearest the front of the table being for quart bottles and the others, in order, for pints, half-pints and quarter pints. By adjusting the hand wheel 68, the position of the slide may be fixed at the desired point, at 35 which the lugs 63 will properly center the bottles.

In the operation of the machine, the attendant stands at the front end and places four bottles in the front transverse row of 40 spaces in the slide 60 at each reciprocation of said slide, the bottles resting at first on the table 12 and later being pushed onto the plate 56 of the elevator. The slide is moved rearwardly by the cam 44 the distance 45 between two transverse rows of filling valves on the tank 16. While the slide is in the position shown in Fig. 1, the elevator is raised, the plates 56 and ribs 55 of the elevator passing up between the bars 62 of 50 the slide to carry the bottles into a plane above the slide. The latter is then moved forwardly to its starting position so that when the elevator is again lowered, the bottles will occupy rows of spaces next rearwardly from 55 those previously occupied and the front row of spaces will be empty to receive another set of bottles.

When filling quart bottles, each transverse row is raised into successive association 60 with each of the four transverse rows of filling valves, being partially filled at each of the first three rows, and the filling being completed in the last row. After the bottles pass the capping devices 19 they are 65 moved onto the rear end of the table 12 and

are then removed by the operator. When filling bottles of smaller sizes than quarts, it is unnecessary to use all four rows of filling valves, and it has been found to be preferable to raise and suspend one or more rows 70 of valves in inoperative position. For example, with pint bottles the first row of valves is suspended, with half pints the first two rows, and with quarter pints three rows are suspended, leaving only the last row in 75 use for quarter pints. This is accomplished in the following manner:

Each of the valves 17 (see Fig. 3) comprises a milk tube 77 which communicates at its upper end with the interior of the 80 tank 16 and is vertically slidable in a bearing 78 in the bottom of the tank. On the lower end of this tube is threaded a bell 79 and a yieldable bottle closure 80. Within the tube is a smaller vent tube 81 which extends up to a point above the level of the liquid. On the lower end of the vent tube 81 is a valve member or head 82 which closes the lower end of the milk tube 77. A coiled compression spring 83 surrounding the milk 90 tube tends to hold the latter against the valve member 82. When in normal operating position, all of these parts are supported by a spring member 84 which rests upon the bottom of the tank or the bearing 78 and engages a collar 85 on the vent tube 81. The springs 83 and 84 thus work 95 against each other.

Referring to Fig. 4, which shows a portion of the tank 16 in its longer dimension, 100 86 indicates a frame which may be of angle iron and rests upon the upper edge of the tank. A similar frame 87 is secured to the frame 86, but is shorter than the latter, so as to provide cross-beams for supporting 105 one or more bars 88. Each of these bars has four openings 89 therein of sufficient size to receive collars 90 which are fixed upon the upper ends of the respective vent tubes 81 of the filling valves. When it is desired 110 to suspend a row of filling valves in inoperative position, one of the bars 88 is laid across the frame 87 in a direction transverse to the machine, and the vent tubes 81 are raised to pass the collars 90 thereon through the bar 88, and a two-arm clip 91 is slipped around each vent tube beneath the collar 90 and above the bar 88, so that the vent tube is firmly supported. In thus raising the vent tube, the valve member 82 on the lower 115 end thereof lifts the milk tube 77 and the bell 79 and gasket 80 carried thereby. When in their suspended position, as shown in Fig. 3, the filling valves are at such height as to be out of the way of the bottles when 120 raised by the elevator.

When a row of filled bottles is raised against the row of capping devices 19, said devices rise in the continuing upward movement of the bottles, such rising movement 130

of the capping devices causing them to be actuated to cap the bottles.

I claim as my invention:

1. In a machine for operating upon uncased bottles, a table, a plurality of operating devices supported above said table and arranged in spaced relation in a row extending longitudinally of the machine, means for raising and lowering bottles relative to said devices, bottle-advancing means for positioning bottles directly beneath said operating devices, said means including a bar extending longitudinally of the table and having a plurality of laterally projecting devices thereon spaced apart and each being of a length adapted to directly engage with a bottle to move it, and mechanism for reciprocating said bar adjustable to vary the initial position thereof, said raising and lowering means being adapted to permit when in its raised position the movement of the laterally projecting devices across the path of up and down movement of the bottles.
2. In a machine for automatically operating upon uncased bottles, a table, a plurality of operating devices supported above said table and arranged in spaced relation in a row extending longitudinally of the machine, means for directly engaging the bottles to be operated upon to advance them to a position beneath said operating devices, bottle-elevating means operable to raise and lower the bottles to and from said devices, said advancing means being movable across the path of up and down movement of the bottles when the elevator is in its raised position, and mechanism for actuating the bottle positioning and elevating means, whereby while the elevating means is supporting bottles in raised position the positioning means is returning from its advanced position beneath the operating devices to receive a new supply of bottles.
3. In a machine for operating upon bottles, a base having a table, a tank, means for adjustably supporting said tank above said table, a plurality of filling and capping devices mounted on said tank and arranged in spaced relation in a row extending longitudinally of the machine, bottle-advancing means including a bar mounted on the table and having devices adapted to engage directly with bottles upon the table, an elevator directly beneath said filling and capping devices, and means for longitudinally reciprocating said bar, said bottle-engaging devices being adapted when the bar is moved to position the individual bottles directly beneath said operating devices, said actuating means being adjustable to vary the initial position of the bar, and the devices on the bar being reciprocable across the path of up and down movement of the

bottles when the elevator is in its raised position.

4. A machine for filling and capping bottles having a tank, a plurality of rows of filling valves on the bottom of the tank, a row of capping devices carried by the tank, said valves and capping devices being actuated by pressure of bottles against their lower ends, a support for rows of bottles, means for pressing rows of bottles against said valves and capping devices, a slide having beveled portions adapted to center various sizes of bottles, means for reciprocating the slide, said reciprocating means being adjustable to vary the position of the slide for various sizes of bottles, means for raising and lowering the tank to adjust the position of the valves and filling devices in accordance with variations in the size of the bottles, and means for holding selected valves elevated out of position to be engaged by bottles.

5. A machine for filling and capping bottles comprising a suitable base, a tank located above said base and having a plurality of transverse rows of filling valves, a row of capping devices mounted on the rear side of said tank, upright standards rising from the base and supporting said tank, an elevator mounted beneath the tank and having a plurality of longitudinally extending supporting members for the bottles, a horizontal slide mounted for reciprocation above the normal or lowered position of the elevator, said slide comprising a plurality of longitudinally extending members providing between them spaces to receive individual bottles, said spaces being adapted to permit the supporting members on the elevator to pass up therethrough and raise the bottles into a plane above the slide and into association with the filling valves and capping devices, and mechanism for co-operatively actuating the elevator and the slide to cause the latter to advance bottles while the elevator is lowered and to make its return movement free of the bottles while the latter are held elevated.

6. A machine for acting upon bottles comprising a suitable base, operating means mounted above said base, an elevator mounted in the base beneath said operating means, a horizontal slide mounted beneath the operating means and above the normal or lowered position of the elevator, said slide having bottle-receiving spaces therein arranged to permit the bottle-supporting portions of the elevator to pass upwardly therethrough and hold the bottles elevated into association with said operating means and in a plane above the slide while the latter is moved in one direction, and mechanism for co-operatively actuating the elevator and the slide.

7. A machine for acting upon bottles comprising a suitable base, operating means located above said base, an elevator mounted in the base beneath said operating means, a 5 horizontal slide located beneath said operating means and above the normal or lowered position of said elevator, said slide having a plurality of bottle-receiving spaces which are connected together to form continuous spaces running in the direction of reciprocation of the slide and adapted to 10 permit the bottle-supporting portions of the elevator to pass upwardly therethrough and to permit the slide to make its return movement while the elevator is raised, and mechanism for coöperatively actuating the elevator and the slide. 15

8. A machine for acting upon bottles comprising a suitable base, operating means 20 mounted above the base, an elevator mounted in the base beneath said operating means and adapted to raise bottles to the latter, a slide comprising a plurality of members extending in the direction of reciprocation of 25 the slide and connected together at one end only, said members being shaped to provide bottle spaces and being adapted to receive between them the bottle supporting portions on the elevator, and means for coöperatively 30 actuating the elevator and the slide.

9. A machine for acting upon bottles comprising a suitable base, operating means located above said base, an elevator beneath said operating means, horizontal slide means 35 located beneath said operating means and above the normal or lowered position of said elevator, said slide having means adapted to engage individually a plurality of transverse rows of bottles and move the bottles 40 horizontally, and the elevator being arranged to lift the bottles to said operating means and into a plane above said slide, means to permit the latter to make its return movement free of the bottles, and 45 means for coöperatively actuating the elevator and the slide means.

10. In a machine for acting upon bottles, the combination of the operating means, an elevator for raising bottles to said means, a horizontal slide located between the operating means and the elevator, said slide comprising a plurality of bars extending in the direction of reciprocation of the slide and having means to engage the bottles for 55 advancing them, said elevator having a plurality of upstanding ribs running in the direction of reciprocation of the slide and positioned so as to pass up between said bars and raise the bottles to a plane above 60 the bars, whereby the slide may return free of the bottles, and mechanism for coöperatively actuating the elevator and the slide.

11. A machine for filling bottles comprising a suitable base, standards rising there-

from, a tank supported by said standards 65 and provided with a plurality of filling valves, an elevator for raising bottles to said valves, a table mounted on the base and having an opening through which said elevator may pass, slide means mounted on 70 said table and individually engaging each bottle for horizontally moving the bottles step-by-step, a rock-shaft mounted in the base, two arms fixed on said shaft and connected to said slide means for reciprocating 75 the latter, a rotary cam mounted in the base, and means operable by the cam for rocking said shaft, the cam being arranged to operate the elevator.

12. A machine for filling bottles comprising a suitable base, standards rising therefrom, a tank supported by said standards and provided with a series of filling valves, an elevator mounted in the base and adapted to raise bottles to said valves, rotary 85 cam means mounted in the base and adapted to actuate said elevator, a horizontal slide adapted to move the bottles step-by-step horizontally, a rock-shaft mounted in the base, two arms fixed at their lower ends on 90 said rock-shaft and extending upwardly into operative association with said slide, a downwardly extending arm fixed on the rock-shaft, a lever pivoted in the base and operable by said cam means, said lever being connected to said downwardly extending arm, whereby the cam means will move said slide in one direction, and a coiled spring connected to said lever and arranged to move the slide in the opposite direction. 95

13. A machine for filling bottles comprising a hollow rectangular base, a drip-pan mounted on the upper edge of said base, a table mounted on the drip-pan, a horizontal slide mounted on said table, standards rising from the base, a tank mounted on the upper end of said standards and provided with a plurality of filling valves, an elevator for raising bottles to said valves, means for reciprocating said slide, and cam means arranged to actuate said elevator and said slide reciprocating means. 100

14. A machine for filling bottles comprising a suitable base, a drip pan mounted on the upper end of said base and having a central bearing, an elevator comprising a post slidable in said bearing and having bifurcated guide portions at its lower end, a shaft mounted in the base, a cam member on said shaft, means for rotating said cam 115 member, the bifurcated portions of the elevator posts straddling said shaft and said cam member, a roller carried by the post and resting upon the cam member, a platform on the upper end of the elevator post, 120 a tank provided with filling valves mounted upon the base above said platform, horizontal slide means arranged to advance bottles 125

- horizontally above the elevator, and means operable by said cam member for reciprocating said slide means.
15. A machine for filling bottles comprising a suitable base, an elevator supported therein, a tank mounted on the base above said elevator and provided with filling valves, horizontal slide means for advancing bottles, said slide means having a series of spaces to receive the bottles, guide means upon which the slide means is reciprocably mounted, one of said means being constructed to permit the other to be freely removable therefrom, and actuating means for the slide means, one of the two last mentioned means being constructed to permit the easy detachment of the other therefrom, whereby to facilitate cleansing of the parts.
16. A machine for filling bottles comprising a plurality of transverse rows of filling valves, means for horizontally advancing transverse rows of bottles step-by-step beneath said filling valves, each step being the distance between adjacent rows of valves, means for raising each row of bottles into successive association with every row of valves, and means for suspending one or more rows of valves in inoperative position.
17. A machine for filling bottles comprising a tank, a plurality of rows of filling valves mounted on the bottom of the tank, and means for raising a row of said valves into inoperative position.
18. A machine for filling bottles comprising a tank, a plurality of rows of filling valves mounted on the bottom of the tank, means for horizontally advancing rows of bottles beneath said valves step-by-step the distance between adjacent rows of valves, means for causing relative vertical approaching movement between the tank and the valves on the one hand and the set of bottles on the other, whereby to bring the bottles into association with the valves and open the latter to discharge liquid into the bottles, and means for suspending a row of said valves at such height that the suspended valves will not be opened by the bottles during the mentioned approaching movement.
19. A machine for filling bottles comprising a tank, a plurality of valves mounted thereon, and each having a vent tube, and means for suspending certain of said valves in inoperative position comprising a bar adapted to be supported at the upper portion of the tank, said bar having openings therein through which the vent tubes may pass, collars on the vent tubes, and clips arranged to engage the said collars and rest upon said bar.
20. A bottle-filling machine having, in combination, a tank having a plurality of transverse rows of filling valves, an elevator 65 beneath the tank and having a plurality of longitudinally extending supporting members for the bottles, a horizontal slide mounted for reciprocation above the normal or lowered position of the elevator, said 70 slide comprising a plurality of longitudinally extending members providing between them spaces to receive individual bottles, said spaces being adapted to permit the supporting members on the elevator to pass up 75 therethrough and raise the bottles into a plane above the slide and into association with the filling valves, and mechanism for coöperatively actuating the elevator and the slide to cause the latter to advance bottles 80 while the elevator is lowered and to make its return movement free of the bottles while the latter are held elevated.
21. A machine for operating upon bottles comprising a table, a tank having two filling 85 valves, a standard for supporting said tank above said table, a capping device also mounted on said tank, reciprocatory means for engaging directly with a bottle to move it step by step from a position beneath one 90 filling valve to a position beneath the other and from the last filling valve to a position beneath said capping device, an elevator for raising and lowering the bottle after each 95 movement by said moving means until it has been operated upon by the capping device, said filling valves and capping device being automatically operable by the engagement of the bottle therewith, and mechanism for coöperatively actuating said moving means and said elevator.
22. In a machine for operating upon uncased bottles, a table having an opening therein, a plurality of devices supported above said opening in the table arranged in 105 a row extending longitudinally of the machine and each operable automatically by the engagement of the bottle therewith, bottle-advancing means including a plurality of laterally projecting devices each arranged to directly engage with a bottle to move it beneath the operating devices, and means for raising and lowering bottles normally positioned beneath said devices, said bottle-advancing devices being operable 110 across the opening in the table while the raising and lowering means is elevated.
23. In a machine for operating upon uncased bottles, a table, a plurality of operating devices supported above said table and arranged in a row extending longitudinally of the machine, bottle-advancing means adapted to position bottles directly beneath said operating devices, said means including a bar extending longitudinally of the table 125 and having a plurality of laterally projecting devices adapted to directly engage with the bottles supported on the table, an eleva-

5 tor, and means for moving said bar and the devices thereon to carry the bottles onto and off from the elevator and for actuating the elevator, said bottle-engaging devices being movable across the path of movement of the elevator while the latter is in its raised position.

24. A machine for operating upon uncased bottles having, in combination, a table, a 10 row of operating devices supported above said table, means located above the table and forming a passageway of only sufficient width to receive a single row of bottles, said passageway being in same vertical plane 15 as said row of operating devices, said table having an opening beneath said row of operating devices, and an elevator reciprocable through said opening and passageway to raise and lower bottles relative to said devices, the means forming said passageway 20 including a member reciprocable to advance bottles in said passageway.

25. A machine for operating upon uncased bottles having, in combination, a table 25 having an opening therein, a row of operating devices supported above said opening, means forming a passageway of only sufficient width to receive a single row of bottles, said passageway being in same vertical 30 plane as said row of operating devices and said means including a member having bottle engaging devices thereon, and an elevator reciprocable through said opening and passageway to raise and lower bottles relative to said devices, said member being reciprocable to advance bottles in said passageway.

26. A machine for operating upon uncased bottles having, in combination, a table, 40 a row of operating devices supported above said table, bottle advancing means including a member located above the table having

bottle-engaging devices thereon and operable in a plane parallel to said row of operating devices, said table having an opening beneath said row of operating devices, and an elevator reciprocable through said opening and passageway to raise and lower bottles relative to said devices, said member being reciprocable to move its bottle-engaging devices across the opening in the table to advance bottles in said passageway and to return for a new supply of bottles when the elevator is in its raised position. 45 50

27. In a machine of the class described, a bottle-supporting table having an opening therein, an elevator reciprocable through said opening, and means for advancing uncased bottles comprising a bar having devices each adapted to directly engage with a bottle, said devices being movable across said opening while the elevator is raised. 55 60

28. In a machine of the class described, an elevator, and means for moving bottles onto and off from said elevator including a bar having devices thereon for directly engaging bottles to be moved, said devices being movable across the path of up and down movement of the bottles when the elevator 65 is in its raised position. 70

29. In a machine of the class described, an elevator comprising a plate having a series of notches therein, and means for moving bottles onto and off from said elevator including a plurality of bottle-engaging devices spaced apart and projecting laterally into said notches in the elevator plate 75 in the movement of the elevator.

In testimony whereof, I hereunto set my hand in the presence of two witnesses.

THEODORE L. VALERIUS.

In the presence of—

ROY LAWRENCE,
ARNOLD B. KUENIMAN.
